(57) **CLAIM**

We claim the ornamental design for an LED stick coupler, as shown and described.

DESCRIPTION

FIG. 1 is an isometric view of an LED stick coupler, showing my new design;

FIG. 2 is a front elevation thereof, the rear elevation view being the same;

FIG. 3 is a left elevation thereof; the right elevation, top and bottom plan views being the same; and,

FIG. 4 is a cross section thereof the section being taken along the plane shown in FIG. 2.

1 Claim, 2 Drawing Sheets

FIG. 1

FIG. 2

FIG. 3

FIG. 4
